HIGH-PRESSURE MODULATOR TUBE

Edward G. F. Arnott, Upper Montclair, Charles M. Slack, Glen Ridge, and Clarence E. Dawley, Bloomfield, N. J., assignors to Westinghouse Electric Corporation, East Pittsburgh, Pa., a corporation of Pennsylvania

Application June 19, 1943, Serial No. 491,496

4 Claims. (Cl. 250—27.5)

1

The present invention relates to what is termed a pulse modulator tube or a triggered spark-gap device commonly employed in connection with the transmission of high frequency waves.

Devices of this general type are known to the art but have heretofore been subject to the disadvantages that they have been of relatively short life and operate at comparatively low voltages. Moreover, they have been erratic or unstable in performance.

It is accordingly an object of the present invention to provide a triggered spark-gap device which operates under substantially stable conditions during its useful life.

Another object of the present invention is the provision of a triggered spark-gap device which requires a relatively low triggering voltage to initiate a discharge.

Another object of the present invention is the provision of a triggered spark-gap device which operates with low energy dissipation and will pass comparatively high power after initiation of the main discharge at much lower voltages than otherwise.

A further object of the present invention is the provision of a triggered spark-gap device which is of simple yet rugged construction and thus economical to manufacture.

Still further objects of the present invention will become obvious to those skilled in the art by reference to the accompanying drawing wherein:

Fig. 1 is an elevational view of a triggered spark-gap device constructed in accordance with the present invention;

Fig. 2 shows a slight modification which the triggered spark-gap of the present invention may take;

Fig. 3 is an elevational view showing a still further construction which the spark-gap of the present invention may have;

Fig. 4 is a fragmentary view of another modification of the triggered spark-gap of the present invention;

Fig. 5 is a perspective view of still another modification which the triggered spark-gap device of the present invention may take;

Fig. 6 is a view similar to that of Fig. 5 but showing a slightly different construction of the electrodes of the device, and

Fig. 7 is a fragmentary view identical to that of Fig. 6 except that one of the electrodes of the device is insulated for the greater portion of its length.

Referring now to the drawings in detail, the

2

triggered spark-gap device 5 of the present invention as shown in Fig. 1 comprises an envelope 6 formed of vitreous sections 7 joined together by a metallic section 8. This latter section is likewise formed of two halves which, after complete fabrication of the ends of the device 5, are welded or otherwise hermetically united at their respective flanges 9. In order to form a seal with the vitreous envelope portions 7, the 10 halves of the metallic section 8 are made of a metal such as "Kovar" which has a coefficient of expansion approximating that of the vitreous portions.

The respective ends of the vitreous portions 7 15 are hermetically closed by end caps 10 likewise formed of "Kovar" through which are sealed a pair of electrodes 12 and 13 formed of suitable metal such as iron or tungsten. As will be noted, the opposing electrodes 12 and 13 extend into the 20 device 5 to approximately the center of the surrounding metallic cylinder 8 with just a small spacing of approximately .030 inch between the respective electrode ends.

After fabrication of the device 5, it is treated 25 and exhausted in the customary manner and then filled with an ionizable medium at high pressure prior to sealing-off at 14. As will be hereinafter specifically mentioned, the nature and pressure of the ionizable medium is of considerable importance in determining the operating voltage of the device as well as bearing on its useful life.

The structure as shown in Fig. 2 differs only 30 in minor constructional details from that of the preceding modification. As can be readily seen, the metallic cylindrical center section 22 of Fig. 2 is all of one piece and the electrodes 23 and 24 are sealed to the vitreous end sections 25 of the envelope through reentrant presses 26 and 27, thus dispensing with the Kovar end caps 10 of Fig. 1.

The advantage of utilizing cylinders as shown in Figs. 1 and 2 is that it allows dimensions to be chosen to give a minimum potential gradient 45 at the inner cylinder and a uniform voltage distribution along the electrodes. This accordingly results in wear or erosion of the electrodes being distributed over the entire surface, thus minimizing change in electrode spacing. Moreover, since the metallic cylindrical center section surrounds the electrodes for a large portion of their length and particularly at the gap therebetween, the amount of coating of the glass walls by sputtered metal is reduced because the arc takes place inside the cylinder. Otherwise sputtering eventu-

ally destroys the insulating properties of the vitreous envelope and thus shortens the useful life of the device.

The device of Figs. 1 and 2 operates in the following manner. A potential is applied to the metallic cylindrical center section 8 or 22 and one of the electrodes (13 or 24, for example) is grounded. When an extremely rapid voltage impulse is applied to the other electrode (12 or 23) as a trigger electrode, a discharge is started between the metallic cylindrical electrode 8 or 22 and the remaining grounded electrode 13 or 24. Such discharge is in the form of a low voltage arc which passes very high currents due to production of positive ions in the ionizable medium. Since the ionizable medium is at high pressure, large currents of the order of hundreds of amperes can be maintained without overheating the electrodes since a sufficient number of ions are available to maintain a low arc drop. Due to the nature of the customary circuit, the arc is extinguished after a short interval and the device is then ready for repetitive operations after the ionizable medium is sufficiently deionized to withstand the applied voltage.

Devices constructed as shown in Figs. 1 and 2 have had an envelope diameter ranging from about $\frac{3}{8}$ to 1 inch and electrode diameters approximating .080 to $\frac{3}{8}$ inch with a spacing therebetween of about .030 inch. The smaller dimensioned device operated at from 6 to 12 kilovolts at 1000 cycles when filled with 45 lbs. absolute pressure of nitrogen admixed with 15 lbs. of air, thus making the total pressure of the ionizable medium slightly over approximately 4 atmospheres. With an admixture of 38 lbs. of argon and 15 lbs. of air (or total of approximately 3.6 atmospheres), the device operates at 4 kv. and with air alone at 15 lbs. (approximately 1 atmosphere), the voltage was 6 kv. while the structure of Fig. 2 operated as high as 18 kv. when constructed of dimensions approaching the upper limits.

In the modification shown in Fig. 3 the envelope 32 is entirely of vitreous material with the electrodes 33 and 34 sealed through opposite ends of the envelope in the absence of a reentrant press as in Fig. 2. Also, the trigger electrode 35 is sealed into a side-arm 36 and is ring-shaped so as to surround one of the main electrodes 34. Again, as in the previous modifications, the device is filled with an ionizable medium and a voltage impulse is applied between the trigger electrode 35 and the electrode 34 which initiates a discharge between the electrodes 33 and 34 carrying the main voltage.

The structure of Fig. 4 differs from that of Fig. 3 in that the main electrodes 42 and 43 are brought into the envelope 44 through side-arm reentrant presses 45, as is the trigger electrode 46, the latter of which is of rod-like configuration similar to the main electrodes 42 and 43.

Fig. 5 shows a construction in which the main electrodes 52 and 53 are in the form of "Kovar" cups sealed to the reentrant stems 54 and the trigger electrode 55, although sealed to a side-arm reentrant stem 56, is of disc-shape. This provides a uniform field over the surface of the trigger electrode 55 and prevents the triggering spark from producing ions or radiation in the upper gap between the trigger electrode 55 and the main electrode 52. It does, however, initiate the arc between the main electrodes 52 and 53 in the same manner as described in the preceding modifications by ionizing the gaseous medium.

The modification of Fig. 6 is somewhat similar to that of Fig. 5 in that the main electrodes 62 and 63 are again "Kovar" cups sealed to reentrant stems 64. In this instance, however, the lead-in for the electrode 63 enters through a side-arm reentrant press 65 and the trigger electrode 66 is in the form of a rod or pin extending through an opening 67 in the electrode 63 and sealed through a vitreous wall 68 of the envelope 69.

In triggered spark-gap devices of the present invention the operating voltage, as before mentioned, is determined by the spacing between the electrodes, the gas pressure and the nature of the gas. Likewise the triggering voltage required to initiate the arc between the main electrodes is determined by the gas pressure and spacing between the trigger electrode and the nearest adjacent main electrode. The construction as shown in Fig. 6 possesses the features of rigidity and ability to withstand high internal pressures and allows for considerable wear of the electrodes during operation before expiration of useful life. In addition to the aforementioned gaseous medium, other gases have been employed such as argon, helium, and a mixture of these latter two gases.

Tests with a structure such as shown in Fig. 6 indicates that a mixture of argon and helium is preferable to either gas alone. This is because the kilovoltage range over which the device operates steadily is much greater with such admixture than with either of the gases when used separately. As a specific example of one of such tests wherein the trigger electrode 66 was formed of 100 mil tungsten rod spaced 80 mil from the surrounding adjacent main electrode 63, and using a 50-50 mixture of argon and helium at a pressure of 75 lbs. absolute (about 5.1 atmospheres), the operating voltage ranged from 8.5 to 13.5 kilovolts. At such range the triggering voltage required to initiate the arc between the main electrodes 62 and 63 was 6 kilovolts at a frequency of 500 cycles. This triggering voltage is, however, materially reduced by as much as 50% by the provision of an insulating sleeve 72 which may be of the same vitreous material as the envelope 73 as shown in Fig. 7 with this latter modification being otherwise identical to that of Fig. 6.

It thus becomes obvious to those skilled in the art that a high pressure triggered spark-gap device is herein shown and described which is of simple construction yet operable to periodically control the passage of high power. Moreover, the arc is initiated between the main electrodes by a comparatively low triggering voltage and the device operates with low dissipation over a desired kilovolt range for a commercially useful life of several hundred hours.

Although several embodiments of the present invention have been shown and described, it is to be understood that still further modifications thereof may be made without departing from the spirit and scope of the appended claims.

We claim:

1. A high pressure, triggered, spark-gap device comprising an envelope provided with oppositely disposed reentrant stems, a pair of main electrodes disposed in said envelope and forming an hermetic sealed end-closure for said reentrant stems for supporting a high current arc discharge upon the application of several kilovolts therebetween, an ionizable medium in said envelope at a pressure ranging from one to five atmospheres, and a trigger electrode disposed closer to one of said main electrodes than to the other and

operable upon the application of a potential between said trigger electrode and the adjacent main electrode to cause ionization of the ionizable medium and the initiation of the high current discharge between said main electrodes.

2. A high pressure, triggered, spark-gap device comprising an envelope provided with oppositely disposed reentrant stems, a pair of main electrodes disposed in said envelope and forming an hermetic sealed end-closure for said reentrant stems for supporting a high current arc discharge upon the application of several kilovolts therebetween, an ionizable medium in said envelope at a pressure ranging from one to five atmospheres, and a disc-shaped trigger electrode of relatively large area disposed closer to one of said main electrodes than to the other in the path of the discharge between said main electrodes, and operable upon the application of a potential between said trigger electrode and the adjacent main electrode to cause ionization of the ionizable medium and the initiation of the high current discharge between said main electrodes.

3. A high pressure, triggered, spark-gap device comprising an envelope provided with oppositely disposed reentrant stems, a pair of main metallic cup-shaped electrodes disposed in said envelope and forming a glass-to-metal seal with said reentrant stems for supporting a high current arc discharge upon the application of several kilovolts therebetween, an ionizable medium in said envelope at a pressure ranging from one to five atmospheres, and a trigger electrode coaxially disposed relative to the longitudinal axis of said main electrodes with its end passing through an opening in one of said electrodes in closely spaced proximity thereto and operable upon the application of a potential between said trigger electrode and the adjacent main electrode to cause ionization of the ionizable medium and the initiation of the high current discharge between said main electrodes.

4. A high pressure, triggered, spark-gap device comprising an envelope, a pair of main metallic cup-shaped electrodes disposed in said envelope and forming a glass-to-metal seal with said envelope for supporting a high current arc discharge

upon the application of several kilovolts therebetween, an ionizable medium in said envelope at a pressure ranging from one to five atmospheres, a trigger electrode coaxially disposed relative to the longitudinal axis of said main electrodes with its end passing through an opening in one of said electrodes in closely spaced proximity thereto and operable upon the application of a potential between said trigger electrode and the adjacent main electrode to cause ionization of the ionizable medium and the initiation of the high current discharge between said main electrodes, and an insulating sleeve surrounding said trigger electrode except for the end adjacent the juxtaposed main electrode to decrease the triggering potential necessary to otherwise initiate the high current discharge between said main electrodes.
